UNITED STATES PATENT OFFICE.

ABEL D. TYLER, JR., OF WORCESTER, MASSACHUSETTS, ASSIGNOR OF ONE-HALF TO SAMUEL MAWHINNEY, OF SAME PLACE.

IMPREGNATING WOOD.

SPECIFICATION forming part of Letters Patent No. 553,547, dated January 28, 1896.

Application filed July 7, 1893. Serial No. 479,861. (No specimens.)

To all whom it may concern:

Be it known that I, ABEL D. TYLER, Jr., a citizen of the United States, residing at Worcester, in the county of Worcester and 5 State of Massachusetts, have invented a new and useful Improvement in Processes of Impregnating Wood, of which the following is a specification, reference being had to the accompanying drawings, which represent the apparatus employed for carrying my improved process into effect.

My present invention relates to a process of impregnating wood for various purposes with a foreign material by which the wood may 15 be rendered waterproof or antiseptic, or both, with an accompanying increase in its weight.

My invention has reference to the method of producing such change in the texture of the wood as will secure these desired results 20 by the impregnation of a foreign substance which is normally in a solid or semisolid state and which can be liquefied by the application of a moderate degree of heat, and it relates particularly to the process by which this result is accomplished independently of the 25 foreign substance employed or of the specific result desired. If the wood is to be rendered waterproof, a waterproofing material is selected, if antiseptic an antiseptic material, it being only required that the foreign substance with which the wood is to be impregnated be such as will be capable of liquefaction by the 30 application of a moderate heat and which will readily assume a solid or semisolid condition 35 when the heat is withdrawn.

In the accompanying drawings I have represented an apparatus by which my improved process can be carried into effect, in which—

Figure 1 represents a closed receptacle 40 shown in central sectional view in order to disclose the interior chamber containing an impregnating material which has been reduced to a liquid form by the application of heat and representing a number of wood lasts 45 inserted therein. Fig. 2 represents the closed receptacle in central sectional view, but as having been rotated one-half a revolution in order to carry the lasts above the impregnating liquid during the period of cooling.

Similar letters refer to similar parts in the different figures.

A represents a closed receptacle, preferably made of heavy sheet metal, and mounted upon each end are gudgeons A', supported upon posts A², so the receptacle can be rotated. The 55 receptacle A is about half-filled with a waterproofing material—such, for example, as paraffine—which has previously been heated sufficiently to reduce it to a liquid form.

C denotes the articles to be impregnated, 60 in the present instance wood lasts employed in the manufacture of boots and shoes, the lasts being inclosed within a chamber D at the bottom of the receptacle. Pressure is applied through the pipe E, communicating 65 either with an air-pump or with a reservoir of compressed air and with the interior of the receptacle A through one of the gudgeons A', which is made hollow for the purpose. When the lasts C have remained immersed and under pressure sufficiently long to become thoroughly saturated with the impregnating liquid, the receptacle A is rotated one-half a revolution, carrying the chamber D, containing the lasts, uppermost, as shown in Fig. 2, and free 70 from the impregnating liquid, which flows to the lower half of the receptacle.

The chamber D is formed by dividing the interior of the receptacle by means of a perforated partition D', upon which the lasts 80 rest when the receptacle is rotated into the position shown in Fig. 2.

The pressure is allowed to remain until the lasts have become cooled, when they are removed and the paraffine is again liquefied by 85 the application of a steam-jet or other means.

The receptacle A is provided with openings F to allow access to the interior of the receptacle, and the openings are hermetically closed by the covers F' in the usual manner. 90

The process forming the subject of my present invention is applicable to a great variety of purposes, and is especially adapted for the purpose of rendering such articles of wood waterproof as do not permit of a variation in 95 their size—such, for example, as the wood lasts employed in the manufacture of boots and shoes, which are made of the exact size required and would be rendered worthless by a slight variation in size. In some of the processes of boot and shoe manufacture a wet 100 insole is applied to the last, which absorbs

the moisture from the insole, causing an increase in the size of the last.

In rendering a wood last waterproof by my improved process I prepare the last in the usual manner of thoroughly-dried material and exact size required. I then place the last in a closed receptacle capable of resisting considerable pressure and immerse it in a waterproofing material, like paraffine, which is rendered liquid by the application of a moderate amount of heat. I then apply a pressure to the liquefied paraffine with the lasts immersed therein of, preferably, from fifty to one hundred and fifty pounds to the square inch, which causes the liquefied paraffine to be forced through the interstices of the last. After the last has been thoroughly impregnated with the melted paraffine it is allowed to cool before the pressure is removed, so as to cause the paraffine held within the interstices of the last to become "set" or partially solidified. A preferable method is to partially fill the closed vessel with the melted paraffine, leaving an air-space in its upper portion, into which the immersed last can be raised free from the melted paraffine during the period of cooling, which allows the cooling process to be continued under pressure until the paraffine contained in the last has become so cooled and solidified as to be securely locked within the interstices of the last. The last may be supported upon a screen or cage, by which it can be lifted out of the melted paraffine, or it may be held at the bottom of the closed vessel during the period of impregnation and the closed vessel rotated to carry the last uppermost and clear it from the liquid paraffine; but whether the last is left immersed in the paraffine or raised therefrom the pressure must be continued until the material becomes sufficiently set so as to be locked within the interstices of the wood. Before the last is immersed in the paraffine I cover its surface with a solution of gum, such as shellac, which is allowed to thoroughly dry, and when the last is immersed in the liquid paraffine and subjected to pressure as above described the paraffine will be driven through the coating of shellac into the interstices of the last, thoroughly impregnating it with paraffine, so that when the last is cooled and the pressure removed the paraffine which has become solidified within the body of the last will be securely locked within the interstices of the last and beneath the coating of shellac, which will remain upon the outer surface, forming a smooth finished surface.

Lasts prepared in this way will effectually resist the application of water or moisture applied to their outer surface, allowing a wet insole to be used in the manufacture of the boot or shoe without a perceptible increase in the size of the last.

Other waterproofing material than paraffine can be employed for this purpose, it only

being necessary that the material selected shall be capable of liquefaction with a moderate amount of heat, which will not injuriously affect the character or size of the article to be operated upon and which is of a homogeneous nature, allowing it to be readily forced within the pores of the wood by the application of pressure and one which will also re-assume its solid or semisolid condition under pressure when the heat is removed. I have found by experiment that paraffine-wax is well adapted for the purposes of waterproofing articles, such as wood lasts, but various other substances can be employed with good results.

When the last has been treated by the process above described, it will have increased in weight equal to the weight of the foreign substance forced therein, and as the amount of the substance which can be forced into a given area of wood depends chiefly upon its bulk a greater or less increase in the weight of the wood can be secured by the selection of heavier or lighter substances to be forced into it.

By my improved process the wood can be rendered waterproof by the introduction of a waterproof material, antiseptic by the introduction of a preservative material, or the color of the wood may be changed, such as the change in color from a white-grained wood to that of ebony, by the introduction of suitable coloring material.

Whatever the specific result may be which it is desired to accomplish, the essential steps in the process remain the same, the characteristic feature being to cause the foreign material to become securely locked with the pores of the wood, owing to its solidification by the process of cooling while under pressure, so it will not exude from the surface of the wood.

I am well aware that liquid substances have been forced into wood under pressure and also that waterproofing material has been applied to wood when hot—such, for example, as the application of hot oil or by the boiling of the wood in oil, and I do not claim either of these processes; but

What I do claim as my invention, and desire to secure by Letters Patent, is—

1. The within described process of impregnating wood, with a foreign solid, or semi-solid substance, capable of liquefaction by heat and consisting in liquefying the foreign substance by the application of heat; immersing the wood in the liquid under pressure until the desired degree of impregnation of the wood is obtained, then elevating the wood from its bath and allowing the wood so impregnated to cool while under pressure, where-by the substance forced into the interstices of the wood becomes set by its solidification, substantially as described.

2. The within described process of impregnating wood with a solid, or semi-solid substance, capable of liquefaction by heat, and

consisting in rendering the substance liquid by the application of heat, covering the wood to be treated with a solution of gum, such as shellac, immersing the wood in the liquid, applying pressure to force the substance into the interstices of the wood, and beneath the covering of gum, and allowing the wood to cool while still subjected to pressure whereby the impregnating substance becomes set by solidification, substantially as described.

Dated this 1st day of July, 1893.
